UNITED STATES PATENT OFFICE.

JOSEPH T. WHALEN, OF RHINELANDER, WISCONSIN.

CLOCK DIAL.

Application filed January 3, 1921. Serial No. 434,524.

To whom it may concern:

Be it known that I, JOSEPH T. WHALEN, a citizen of the United States, residing at Rhinelander, county of Oneida, and State 5 of Wisconsin, have invented new and useful Improvements in Clock Dials, of which the following is a specification.

My invention relates to improvements in clock dials, said improvements being such 10 as to be useful for instructional or educational purposes.

My invention has for its object the provision of a clock with a dial which will facilitate the instruction of students in the 15 use of a clock.

Another object of my invention is to provide a clock dial which, when used for instructional purposes, will not only teach the students the use of a clock but will 20 familiarize them with the alphabet and the numerical system.

In the drawings:

Figure 1 is a front elevation of a clock provided with a dial embodying a preferred 25 form of my invention.

Figure 2 is a front elevation of a clock having a dial illustrating a modified form of my invention.

Figure 3 is illustrative of an embodiment 30 of my invention in a dial alone, means being provided whereby the hands may be operated manually without the association of a clock mechanism therewith.

Figure 4 is a detail view illustrating the 35 manner in which distinctive colorings are used to identify each of the hands with one of the rows of characters.

Like parts are identified by the same reference characters throughout the several 40 views.

The clock 1 with which my improved dial is associated may be of any suitable form. Preferably however, it is provided with minute and hour hands of two different 45 colors, for example, the hour hand 2 may be black and the minute hand 3 may be red. These hands 2 and 3 are adapted to be moved by the clock mechanism within casting 1 over the surface of a dial 4 of novel 50 form. A number of concentric circles shown at 5, 6 and 7 are inscribed upon the dial of the clock adjacent to its periphery for the purpose of marking off annular 55 spaces adapted to receive numerals and other characters, as will be hereinafter described.

The annular space between lines 5 and 6 will be divided into sixty parts corresponding to the number of minutes in an hour whereby the movement of the minute hand 60 across the interval between any two adjacent dividing lines will indicate the lapse of one minute of time in the manner well known in the art. Each fifth dividing line 65 8 is made heavier than the ordinary dividing or minute lines 9, in the usual manner, to facilitate the reading of the time. Suitable numerals reading consecutively from I to XII are used to designate each of the heavier minute marks 8. Preferably these 70 numerals are of the Roman type, for inasmuch as the clock dial embodying my invention is intended for instructional purposes I desire to familiarize the students with the Roman numeral system, which is ordinarily less well known than the system of Arabic numerals in more common use. If desired, another concentric spacing circle 15 may be provided within the series of Roman numerals and a second series 16 of numerals 80 using the Arabic characters may be placed within the line 15, each Arabic character being in juxtaposition to the corresponding Roman numerals, as indicated in Figure 2.

In the annular space between lines 6 and 7 I provide a row 20 of the first twenty-four letters of the alphabet disposed consecutively, starting with A immediately beneath the minute division line which is customarily designated upon a clock dial by 90 the figure VI and proceeding counter-clockwise around the dial marking each five minute mark with one letter and have one letter between each of said points. For example, adjacent to the figure VI will be 95 found the letter A and next to the figure V, the letter C while halfway between these two figures will be found the letter B. In similar manner the numeral IV will be in proximity to the letter E and the numeral 100 III to the letter G.

In the outer space upon the dial which lies between line 7 and the periphery I have provided a second row 25 of letters comprising, seriatim, the first 24 letters of the alphabet beginning with the letter A adjacent to figure XII at the top of the dial and proceeding thence counter-clockwise about the dial to a termination with the letter X at the intermediate point between the numerals 110 XII and I, as clearly appears in the drawings.

The two rows 20 and 25 of alphabetical characters may be colored similarly if desired. Preferably however, I make the inner row 20 with black characters and make 5 the characters of the outer row 25 red. In this way the characters of row 20 correspond in color to the hour hand 2, while the characters of row 25 correspond in color to the minute hand 3. Another way of 10 attaining the same result is to make the characters of both of the above rows of one color, but to provide different colors of backgrounds which will correspond to the colors of the two hands of the clocks. For example the clock hands might remain black 15 and red and the alphabet characters might be printed in white on backgrounds respectively black and red.

If so desired the dial 4 need not be connected to a clock mechanism but may be used independently, the various circles and 20 rows of characters being inscribed upon a sheet of cardboard which will be provided with a pin 26 upon which will be pivoted 25 the hands 2 and 3. The hands 2 and 3 may then be adjusted manually to any point which seems desirable for the purposes of instruction.

My device may be used as follows:—
30 The instructor, with a number of pupils before him, and with my improved clock dial within the view of the pupils, will set the hands to any desired point upon the dial and will then call upon the pupils to state 35 what time is represented by that position of the hands, and what letter of the alphabet each hand points to; or without moving the hands at all he may take pieces of chalk corresponding in color to the color of the 40 hands and write upon the blackboard a letter of each color. The pupils will then be called upon to state what time is represented by the colored alphabetical characters so drawn upon the blackboard. In so doing 45 they will consider the clockhand of a given

color as pointing toward the letter of the same color which was written on the blackboard by the instructor. If it is preferred to conduct the class orally, it may be understood between the instructor and pupils that 50 the first alphabetical character mentioned by him will be understood to be black and the second alphabetical character mentioned by him will be understood to be red or vice versa. He may then name in rapid succession 55 any two of the alphabetical characters appearing upon the dial of the clock and the pupils may be tested to see how rapidly they can reply in terms of time represented by the characters so named.

It will be apparent that by the use of my improved clock dial, as above described, a child will very rapidly learn to tell time, to recognize the use of the Arabic and Roman numerals, and to know the letters of 60 the alphabet presented on the dial in their natural sequence. My invention will, therefore, prove very valuable in the kindergarten, the home, and in schools for foreigners.

I claim:

1. The combination with a clock mechanism, of a dial operatively associated therewith, hands of different colors adapted to be rotated by the mechanism around the 75 dial, an annular row of figures designating hours upon the dial, and concentric rows of alphabetical characters, each characterized by a color identifying it with one of the 80 hands.

2. A dial, a pair of hands pivotally secured to the center thereof and adapted to be rotated about the pivot point, an annular row of figures upon the dial, and a plurality of concentric rows of other characters 85 significantly related to the figures, each of said last named rows being physically identified with one of the hands.

JOS. T. WHALEN.
